COMPARTMENTED ARM CHAIR

Luella A. Simmons, Los Angeles, Calif.

Application March 7, 1952, Serial No. 18,825

Term of patent 14 years

(Cl. D15—8)

To all whom it may concern:

Be it known that I, Luella A. Simmons, a citizen of the United States, residing at Los Angeles, in the county of Los Angeles, and State of California, have invented a new, original, and ornamental Design for a Compartmented Arm Chair, of which the following is a specification, reference being had to the accompanying drawing, forming part thereof.

Fig. 1 is a side perspective view of a compartmented arm chair showing my new design;

Fig. 2 is another side perspective view thereof as it appears with the lids and drawer in open position; and

Fig. 3 is a top plan view of the compartmented arm chair shown in Fig. 1.

I claim:

The ornamental design for a compartmented arm chair, as shown.

LUELLA A. SIMMONS.
